UNITED STATES PATENT OFFICE.

JOHN GOOD, OF GARDEN CITY, NEW YORK, ASSIGNOR TO GOOD INVENTIONS CO., OF NEW YORK, N. Y., A CORPORATION OF NEW YORK.

LIQUID-FUEL COMBUSTION APPARATUS.

Application filed June 21, 1920. Serial No. 390,354.

The invention relates to liquid fuel burners, and more particularly suction-operated and spark-ignited burners, used for vaporizing and perfecting the charge mixtures of internal combustion engines and consists in certain developments of the combustion method set forth in my prior application Serial No. 222,557, filed March 15, 1918, and in the application thereof to engine uses, although not limited thereto as will be later made apparent. According to said method related flows of liquid fuel and air bearing the relative proportions of an explosive mixture are formed into mixture portions which are relatively rich in fuel and lean in fuel, respectively, these mixture portions being rapidly brought together in the zone of ignition and combustion to produce flame. By this method of combining fuel and air, it is possible to produce non-explosive but very rapid combustion although the fuel and air may be within the proportion limits of explosive mixtures, as used for example in internal combustion engines. Such proportions are difficult to burn non-explosively so as to give a steady flame, without popping, especially in confined passages.

According to this invention, substantially the aforesaid method is carried out in a simple way and the rich and lean mixtures are formed out of a flow of previously measured fuel and air by the control of such flow while in transit to the ignition space and said flow is produced by a pressure difference established between the entrance and outlet of the burner mechanism which will be herein treated as caused by the suction effect created in the in-take of an internal combustion engine. By producing the rich and lean portions in this way the burner apparatus is materially simplified and reduced in size and thereby particularly adapted for compact organization with a carburetor and moreover, the desired rate of combustion is attained by very moderate pressure differences or suction effects such as obtain in carburetors, which specially adapt the invention for operation under the conditions present in automotive engines.

In the accompanying drawings, Figure 1 represents a suction burner-carburetor combination illustrating one manner of carrying out the invention.

Figure 2 is a modification of Fig. 1;

Figure 3 illustrates different means of separating the flow into the rich and lean mixtures;

Figure 4 being a detail of the means for measuring the fuel and air supplies;

Figure 5 is a modification of the separating means of Fig. 3;

Figure 6 shows a modification of Fig. 5 in its practical application;

Figure 7 illustrates still another means of effecting separation; and

Figures 8 and 9 show another method in different embodiments as later explained.

Figure 1 shows a portion of the intake pipe 1 of an internal combustion engine, for example an automotive engine, connected to a conventionally illustrated carburetor 2, the latter having the usual float-controlled or constant-level liquid-receptacle 3 and throttle 4 for controlling the mixture flow through the intake passage to the engine.

The suction effect present in said passage when the engine is in rotation, either by the operation of a starting agency or by its own combustion, is transmitted to the burner and serves to operate it as presently explained,

the flame or burner products being drawn into the intake passage along with the normal charge mixture vaporizing the latter and thus helping the engine start in cold weather as well as improving its operation under running conditions.

The suction connection to the burner in the present case is through the small holes in the wall of the intake passage which holes represent the burner outlet and are marked 5 in this figure, but the apparatus may be connected in other ways and with other devices adapted to maintain an equivalent pressure difference between its entrance and outlet ends, as will later be apparent.

The burner in Fig. 1, comprises a casing 6 provided with an air entrance 7 in the form of an open Venturi tube and with a fuel nozzle 8 having its orifice centered in the throat part of the tube, and supplied with fuel by a tube 9 from the liquid receptacle 3. The suction in the burner produces, coincidentally, an inward flow of air through the entrance 7 and an inward spray of liquid fuel from the nozzle 8. The burner contains an inner cylindrical distributing shell 10, the

interior of which is in communication with the burner outlet 5 and forms the combustion space of the burner. This shell is provided with a funnel shaped deflector entrance 11 protruding more or less into the inner end of the Venturi tube 7 and having such shape and location that some of the air and a large part of the liquid spray is drawn into it, the remaining spray and air being drawn around the exterior of the deflector through the annular space between the shell and casing and through the mixing and distributing holes 12 near its outlet end. The fuel and air entering by way of the deflector entrance 11 constitute a relatively rich mixture, and that entering by way of holes 13, a relatively lean mixture. The total proportions of air and fuel arriving in the combustion space in this way are determined by the corelation of the fuel entrance 8 and the air entrance 7 and these entrances, or their connected appurtenances, are designed or adjusted to measure and deliver proportions which will produce efficient and clean combustion inside the mechanism, under all the circumstance of use. The lean mixture joins the rich mixture inside the shell or mixing space and there the resulting mixture is ignited and then combustibly combined, resulting in flame or flame products passing through the burner outlet to the engine. The combustion is continuous in the sense that it is not explosive in character, and it is also particularly efficient for producing a very rapid development of heat because of the preliminary partial mixture of the fuel and air. Since the object in all combustion processes is to combine all of the atoms of fuel with appropriate atoms of oxygen as quickly as possible, it is plain that by first mixing some of the fuel with what would otherwise constitute the combustion supporting air of the burner, the combination referred to is already partly effected before the combustion zone is reached and the eventual combination constituting combustion is therefore completed with greater promptness than would otherwise be the case. The non-explosive character of such combustion occurs from the absence of any homogeneous mixture of explosive proportions through which flame can propagate with explosive velocity; neither the rich nor the lean have such proportions. Ignition is obtained by a spark-plug screwed into the main casing with its igniting end or spark-gap in the path of the relatively rich mixture, this position being preferred because if the said mixture is sufficiently rich, ignition may be obtained without resorting to the expedient of initially increasing the fuel delivery when the device is first set in action. The degree of richness of the rich mixture is obviously controlled in this form of the invention, by the shape and position of the de-

flection and guiding entrance but the reliability of ignition is improved especially in cold weather, if the initial fuel delivery is also momentarily increased, when the device is first set in action. For this purpose, a number of contrivances may be used as will later appear. In the case shown, the burner fuel tube 9 dips into a well 13 open at its top to the atmosphere and communicating at its bottom with the constant-level fuel receptacle 3, through a restricted passage 14. The upper part of the well is of larger diameter than the lower part and when the burner is idle the liquid level stands in this upper part about as indicated by the dotted line. The lower end of the fuel tube is closed and the fuel enters it by way of the series of fine holes bored in its side in different vertical positions. When the burner is started, the suction effect on the nozzle 8 draws off the liquid in the upper part of the well, at first quite rapidly, due to the short lift, until the level falls to the narrower part and at some point in the latter it finds a constant height at the level of one of the lateral holes and according to the particular degree of suction acting on the burner. The copious delivery occurring while the level is falling makes the mixture condition in the burner combustion space momentarily overrich, so that ignition is readily and reliably attained by spark under all conditions. After the level reaches the narrow part of the well the fuel delivery occurs at that rate which makes the proportions of the burner mixture suitable for burning completely and with cleanliness, and about the same as are used in the carburetor. Changing suction effect in the burner will correspondingly vary the level in the well thereby changing the head against which the fuel must be lifted as well as the amount of air drawn in through the lateral holes, and so as to compensate for the tendency of air-induced liquid flow through small orifices to grow overrich on increasing delivery and keeping the burner proportions constant. This compensating method of fuel delivery enables the burner to operate properly at different rates of combustion, that is to say, to deliver flame or flame products in variable amounts to the intake passage coincidently with variation in the operation of the engine.

It will be understood that the spark-plug is connected to some appropriate source of current as, for example, to the distributor head of the engine's ignition system, or a magneto or otherwise, so that when the engine is started the burner will be ignited automatically, and also that the burner and carburetor may be structurally combined or built together if desired so as to constitute but a single unit.

In Fig. 2, the means for forming rich and lean mixtures is substantially the same as in

Fig. 1, but in this case the funnel-shaped entrance 26 controlled by a reed valve 27 separating or deflecting and guiding member 15 is used without the distributing shell, its rim being held by screws and spacers at a 5 distance from the casing end wall so that the lean mixture enters the combustion space around the edge of the deflector and nearer to the entrance end of said space than in the preceding figure. The rich mixture enters 10 through the deflector as before, and the spark-gap or heat source of the igniter is located in its path. Both the lean and rich mixtures enter the combustion space downwardly and transversely to the main or 15 longitudinal axis thereof, so that the resulting flame or burning mixture is required to turn a corner before reaching the outlet holes. This has the effect of further hastening 20 the mixing effect, results in a shorter and hotter flame and correspondingly permits the use of a smaller structure for a given heating effect. It is specially efficacious for these purposes when used for combustibly combining lean and rich mixtures, for reasons 25 which will already be apparent, but it is not limited to use therewith. The burner outlet in this case is similar to that in Fig. 1 and its several holes 16 open into the intake passage 17 of the carburetor 18 which 30 appears in the background in this figure, 19 being its throttle and 20 its float-controlled liquid receptacle.

Fuel for the burner nozzle 8 is taken directly from this receptacle by the tube 21 35 controlled by needle valve 22 and compensation is afforded by interposing a spring-seated valve in the air path to the burner, which valve has the same effect as the compensating well and tube of the preceding figure, but does not of itself provide the initially rich effect to facilitate ignition. This valve is constituted by a reed 23 screwed over a hole in a cap screwed to the burner air entrance and its mode of action on the 40 fuel delivery is by its control of the suction effect inside the burner as will be obvious. I have ascertained that this type of valve is particularly accurate in maintaining correct fuel proportions and it is 45 of course cheap to construct and apply. It will, of course, be understood that the total proportions of the mixture in the burner may be made initially rich for facilitating ignition when starting, if desired, either by 50 momentarily restricting the air entrance or by any other means.

Figure 3 illustrates an alternate way of 55 separating the measured supply of fuel and air into rich and lean mixtures and as applied to the same general combination of burner and carburetor as shown in Fig. 2. In this case the measured portions of fuel 60 liquid and air are drawn by a mixture tube 24 from a well tube 25 in the carburetor 65 receptacle 20 (see Fig. 4) and from an air

70 separating or deflecting and guiding member 15 is used without the distributing shell, its rim being held by screws and spacers at a distance from the casing end wall so that the lean mixture enters the combustion space around the edge of the deflector and nearer to the entrance end of said space than in the preceding figure. The rich mixture enters 75 through the deflector as before, and the spark-gap or heat source of the igniter is located in its path. Both the lean and rich mixtures enter the combustion space downwardly and transversely to the main or longitudinal axis thereof, so that the resulting flame or burning mixture is required to turn a corner before reaching the outlet holes. This has the effect of further hastening 80 the mixing effect, results in a shorter and hotter flame and correspondingly permits the use of a smaller structure for a given heating effect. It is specially efficacious for these purposes when used for combustibly combining lean and rich mixtures, for reasons which will already be apparent, but it is not limited to use therewith. The burner outlet in this case is similar to that in Fig. 1 and its several holes 16 open into the intake passage 17 of the carburetor 18 which appears in the background in this figure, 19 being its throttle and 20 its float-controlled liquid receptacle.

Fuel for the burner nozzle 8 is taken directly from this receptacle by the tube 21 controlled by needle valve 22 and compensation is afforded by interposing a spring-seated valve in the air path to the burner, which valve has the same effect as the compensating well and tube of the preceding figure, but does not of itself provide the initially rich effect to facilitate ignition. This valve is constituted by a reed 23 screwed over a hole in a cap screwed to the burner air entrance and its mode of action on the fuel delivery is by its control of the suction effect inside the burner as will be obvious. I have ascertained that this type of valve is particularly accurate in maintaining correct fuel proportions and it is of course cheap to construct and apply. It will, of course, be understood that the total proportions of the mixture in the burner may be made initially rich for facilitating ignition when starting, if desired, either by momentarily restricting the air entrance or by any other means.

Figure 3 illustrates an alternate way of separating the measured supply of fuel and air into rich and lean mixtures and as applied to the same general combination of burner and carburetor as shown in Fig. 2. In this case the measured portions of fuel liquid and air are drawn by a mixture tube 24 from a well tube 25 in the carburetor receptacle 20 (see Fig. 4) and from an air

85 separating or deflecting and guiding member 15 is used without the distributing shell, its rim being held by screws and spacers at a distance from the casing end wall so that the lean mixture enters the combustion space around the edge of the deflector and nearer to the entrance end of said space than in the preceding figure. The rich mixture enters 85 through the deflector as before, and the spark-gap or heat source of the igniter is located in its path. Both the lean and rich mixtures enter the combustion space downwardly and transversely to the main or longitudinal axis thereof, so that the resulting flame or burning mixture is required to turn a corner before reaching the outlet holes. This has the effect of further hastening 90 the mixing effect, results in a shorter and hotter flame and correspondingly permits the use of a smaller structure for a given heating effect. It is specially efficacious for these purposes when used for combustibly combining lean and rich mixtures, for reasons which will already be apparent, but it is not limited to use therewith. The burner outlet in this case is similar to that in Fig. 1 and its several holes 16 open into the intake passage 17 of the carburetor 18 which appears in the background in this figure, 19 being its throttle and 20 its float-controlled liquid receptacle.

Fuel for the burner nozzle 8 is taken directly from this receptacle by the tube 21 controlled by needle valve 22 and compensation is afforded by interposing a spring-seated valve in the air path to the burner, which valve has the same effect as the compensating well and tube of the preceding figure, but does not of itself provide the initially rich effect to facilitate ignition. This valve is constituted by a reed 23 screwed over a hole in a cap screwed to the burner air entrance and its mode of action on the fuel delivery is by its control of the suction effect inside the burner as will be obvious. I have ascertained that this type of valve is particularly accurate in maintaining correct fuel proportions and it is of course cheap to construct and apply. It will, of course, be understood that the total proportions of the mixture in the burner may be made initially rich for facilitating ignition when starting, if desired, either by momentarily restricting the air entrance or by any other means.

Figure 3 illustrates an alternate way of separating the measured supply of fuel and air into rich and lean mixtures and as applied to the same general combination of burner and carburetor as shown in Fig. 2. In this case the measured portions of fuel liquid and air are drawn by a mixture tube 24 from a well tube 25 in the carburetor receptacle 20 (see Fig. 4) and from an air

a lean mixture around the margin of the screen. The screen in this case is vertical. The air passage is provided with air cooling fins 32 to aid in keeping the nozzle below the vaporizing temperature of the liquid and the latter is supplied to the nozzle by a tube 33 which may be assumed to be connected to a compensating well like the tube 9 in Fig. 1.

10 Fig. 6 shows the same type of burner and mixture producing means wherein the fuel tube 33 is connected in the usual way to the float receptacle 20 of the carburetor and under the control of a regulating needle valve 15 34. The burner air in this form is admitted through an entrance passage 35 under the control of a reed valve 36, which acts in the same manner as the corresponding valve in Fig. 4 to maintain predetermined or constant proportions of the fuel and air admitted to the burner. The correlation of this burner to the carburetor is described below.

15 In Fig. 7 the mixture of air, admitted at the hole 37, and fuel admitted through the compensating fuel well 13 as above described, is conducted by a mixture tube 38 and discharged through its orifice 39 against a screen 29 as in preceding figures but in this case the tube 38 is looped and most of the liquid therein, after first impinging on the outer wall of the curve under the centrifugal effect, thereafter flows along the inner wall of the curve and issues from the nozzle 39 on the loop side, or the right hand side 20 in the figure, and impinging on the screen directly opposite that side of the orifice makes a relatively rich mixture stream in the line of the spark-gap, while the lean mixture passes through the screen on the left hand side. Otherwise the action of this burner is the same as already described. Upon ignition the lean and rich mixtures combine rapidly but non-explosively and the flame or flame products proceed through the outlet holes to the intake passage 1 with the effect above explained. It will be apparent in this form that the screen merely transmits and perfects the separated mixture portions already partly separated in transit to the burner, and likewise that other means for so transmitting or guiding the mixtures may take its place.

25 In Fig. 8 a mixture of previously measured proportions is produced from a liquid jet derived from a compensating well 13 as already described and from air admitted from atmosphere by the hole 40. This mixture is drawn through a nozzle 41 directly into the combustion space of the burner and transversely to its main axis, or to the general direction of flow therethrough, so that the liquid particles therein, particularly the heavier particles by reason of their inertia, impinge against the opposite wall while the finer particles and much of the air are drawn

more or less directly from the nozzle in the direction of the burner outlet. The impinging heavy particles produce a rich mixture flowing along the opposite wall and over the spark-plug terminals while the finer particles form a lean mixture flowing along the other side, and both mixtures are promptly combined under combustion though sufficiently separate from each other at the ignition point to permit ignition without explosion. The production of lean and rich mixtures in this case occurs by the effect of the inertia of the liquid under a sufficient entrance velocity and by the general shape and dimensions of the combustion space, which is longer than wide, but it will be plain that other shapes and different dimensions may be utilized to cause a directing and guiding surface to produce a sufficient separation to secure the results referred to. The total mixture proportions are made initially rich in fuel in this case by the use of the compensating well having a wider diameter at its upper end as in Fig. 1.

30 The formation of rich and lean mixtures by the inertia effect above described is effective and specially desirable for avoiding explosive ignition when the total proportions are those of an explosive mixture, but it is also usefully employed when the aggregate proportions of the rich and lean mixtures is too rich to explode (if homogeneously mixed or not separated). Fig. 9 illustrates a manner of use under this special condition. Here the liquid fuel is drawn in by fuel tube 42 and nozzle 43 and air by the reed-valve-controlled air entrance 44, the latter serving to maintain a proper compensation. This mixture is delivered by the mixture nozzle 45, transversely to the combustion space so as to form a rich mixture stream along the bottom wall and across the spark-gap and a leaner mixture near the corner 46, but the aggregate of the proportions of both mixtures is not in this case suited for the character of combustion desired for which reason more air is admitted to the two mixtures, while in the act of combustion. This auxiliary air enters by way of a ring of holes 47 direct from atmosphere. It will be quite apparent that auxiliary air could also be admitted in like manner to some of the other forms above described, if the aggregate proportions of the lean and rich mixtures were correspondingly modified and it is not a departure from the principles above set forth if more than two streams of mixtures of different proportions be admitted and combustibly combined in the burner, and even, though one of the streams should be air without fuel, as in the case just mentioned.

35 It will be apparent that the manner of connecting the burners above described to

the suction intake of the engine is subject to variation according to the objects desired. In Fig. 1 the burner outlet holes 5 are disposed on opposite sides of the throttle 4 when the latter is closed or set at its idling position. The outlet hole on the engine side is preferably smaller than the one on the carburetor side. This form of burner connection has special advantages quite independent of the specific character of burner itself and is herein independently claimed. The rate of combustion and the range of engine operation through which the burner operates, depend upon the suction transmitted to it and that again depends on the size of the burner outlet. The double outlet on opposite sides of the throttle transmits sufficient suction through the smaller hole or from inside the throttle when the latter is closed or partly closed to enable the burner to start when the engine is being cranked, as well as later when it picks up, and is idling and also provides enough suction through the larger, outside outlet to keep the burner going when the throttle is opened wider and the intake suction has therefore diminished. In other words, the said arrangement has the effect of providing a large outlet when the intake suction is low and a smaller one when it is higher, and thereby assures an adequate or a desired range for the operation of the burner, quite as though the movement of the throttle effected a mechanical variation of the cross area of the burner outlet, and without disturbing the action of the engine.

In the case of carburetors provided with chokers, as indicated at 50 in Fig. 1, it is apparent that the full force of the intake suction would be transmitted to the burner if the engine should be cranked with the choker closed and that it might result in excessive or imperfect burner operation and to prevent such occurrence, I provide the carburetor with an auxiliary limiting spring-seated air valve adapted to admit air sufficient to relieve an excessive vacuum if created by closing the choker. This may be mounted at any point outside the throttle and in Fig. 1 is located just inside the choker and consists of a spring reed 51 of the same type as that already described but of greater tension.

Such a suction-limiting air vent may also be incorporated in the burner itself as shown for example in Fig. 6, where a similar reed valve 52 is mounted in the wall of the entrance 35, outside of the compensating reed valve 36 already described. In this particular form of carburetor burner combination the carburetor proper is supplied with a choker 53 and the burner air entrance is provided with an individual choker 54 and the two are linked together as shown and arranged for simultaneous closure or ad-

justment by the pull rod 55. The effect of both chokers is to increase the suction so as to make the mixtures produced in carburetor and burner respectively, temporarily over-rich, as when starting a very cold engine on heavy fuel, but the increase of the suction in the burner is limited by the valve 52 which is normally closed but opens on an excessive suction. The flame from the burner is thus certain to be available for vaporizing the carburetor mixture even under mistreatment of the latter.

I claim:

1. The method of non-explosively burning liquid fuel which consists in causing a pressure difference between the entrance and outlet passages of a combustion space to produce a flow of liquid fuel and air in predetermined measured proportions, directing and guiding said flow so that it forms itself into flows of relatively rich and relatively lean mixtures of fuel and air, igniting the rich flow by an igniter intercepting the same, and combustibly combining said mixtures in said space.

2. The method of non-explosively burning liquid fuels which consists in causing a pressure difference between the entrance and outlet passages of a combustion space to produce a flow of liquid fuel spray and air in measured proportions, directing and guiding said flow so that it forms itself into flows of relatively rich and relatively lean mixtures of fuel and air, the aggregate proportions of which are those of an explosive mixture, initiating combustion by a spark in the rich flow, and non-explosively combining said rich and lean mixtures in said space.

3. The method of non-explosively burning liquid fuels which consists in causing a pressure difference between the entrance and outlet of a combustion space to produce a flow of liquid fuel and air, making said flow initially overrich in fuel and later less rich, directing and guiding said flow so that it forms itself into flows of relatively rich and relatively lean mixture portions, igniting the same during the initial rich period and then mixing and combustibly combining said mixtures in said space during the ensuing period when the proportions are less rich.

4. The method of non-explosively burning liquid fuels which consists in transmitting suction to a combustion space, admitting liquid fuel and air thereto under the suction effect, forming thereof relatively rich and relatively lean mixtures and combustibly combining said mixtures in said space.

5. The method of producing hot fuel mixture for use in internal combustion engines, which consists in transmitting the suction effect of the engine intake to a combustion space, admitting liquid fuel and air thereto under said effect, forming thereof relatively rich and relatively lean mixtures, combus-

6. The method of producing heated fuel mixture for internal combustion engines which consists in utilizing the suction effect of the engine intake to cause a suction flow of air and liquid fuel into a combustion space, making the total proportions thereof initially overrich and later less rich forming thereof relatively rich and relatively lean mixtures and igniting the same during the initial period thereof and continuing the combustible combination of the mixtures in said space, and coincidentally passing the combustion products into said intake.
7. The method of burning liquid fuels which consists in directing a mixture flow of liquid fuel spray and air against the wall of a combustion space so as to cause the larger liquid particles to travel in a predetermined path and form a relatively rich mixture flow, the rest of the fuel forming a relatively lean mixture flow in an adjacent path, igniting said rich flow by an igniter located in the path thereof and combustibly combining said portions within said space.
8. The method of producing heated fuel mixture for internal combustion engines which consists in transmitting suction from the engine intake to a combustion space, admitting liquid fuel and air thereto in predetermined proportions, directing said flow against an interior surface in said space and thereby causing the same to separate into rich and lean portions, igniting said portions while separated, combustibly combining them in said space, and passing the combustion products to the engine intake.
9. The method of producing heated fuel mixture for internal combustion engines, which consists in causing a variable suction of the engine intake to cause a variable mixture flow of liquid fuel and air into a combustion space, maintaining substantially constant proportions of the fuel and air in said mixture throughout the variation in the rate of said flow, abruptly changing the flow direction of the mixture within the space and thereby causing the same to separate into rich and lean mixture portions, igniting said portions in their separate condition by an igniter intercepting the rich mixture, and combustibly and non-explosively combining said portions within the space.
10. A liquid fuel burner comprising means for creating a mixture flow of liquid fuel and air, a deflector surface intercepting the flow and forming the same into relatively rich and lean mixture portions, an igniter located in the path of the rich mixture, and a surrounding burner wall enclosing the paths of said rich and lean portions and the igniter and also forming a mixing space for said portions after ignition.
11. A liquid fuel burner comprising an ignition and mixing space, means for creating a mixture flow of liquid fuel and air entering said space transversely to the longitudinal axis or general direction of flow therein, means whereby said entering mixture is caused to separate into relatively rich and lean mixture portions and an igniter in the path of the rich mixture.
12. A suction-operated liquid fuel burner comprising a combustion space connected with a suction passage, means for admitting liquid fuel and air thereto by the effect of said suction and means for forming relatively rich and lean mixtures of said fuel and air for combustible combination in said space.
13. A suction-operated liquid fuel burner comprising a combustion space connected to a suction passage, means for admitting liquid fuel and air thereto by the effect of said suction, means for forming relatively rich and lean mixtures of said fuel and air for combustible combination in said space and an igniter in the space in the path of the rich mixture.
14. A suction-operated liquid fuel burner comprising a combustion space connected to a suction passage, means for admitting liquid fuel and air thereto by the effect of said suction, means for maintaining substantially constant proportions of said fuel and air throughout variation of the suction effect, means for producing relatively rich and relatively lean mixtures of said fuel and air, and an igniter, said space being adapted to mix said mixtures following ignition.
15. Means for producing heated fuel mixture for internal combustion engines comprising in combination a carburettor and a burner both operated by the intake suction and the burner having means for producing and combustibly combining relatively rich and lean mixture flows, and an outlet through which the flame or flame products reach the fuel supplied by the carburettor.
16. Means for producing heated fuel mixture for internal combustion engines comprising a carburettor having a choker and a suction-operated burner connected to the intake passage between the engine and the choker, and a valved air vent operating automatically to limit the degree of suction transmitted to the burner when the choker is closed.
17. Means for producing heated fuel mixture for internal combustion engines comprising in combination with the intake passage and a throttle therein, a burner having its outlet connected to said intake on opposite sides of the throttle.
18. Means for producing heated fuel mixture for internal combustion engines comprising the combination with an intake passage including a carburettor and a throttle,

of a suction-operated burner connected to the intake by plural outlets, one being on the engine side of the throttle when in its restricted position and another on the carburetor side of the throttle.

19. Means for producing heated fuel mixture for internal combustion engines comprising the combination with an intake passage and throttle, a suction-operated burner having an outlet into said passage on opposite sides of the throttle and the outlet on the engine side of the throttle being smaller than that on the opposite side.

20. In apparatus of the kind described a suction operated burner having an igniter and fuel and air entrances and a reed valve controlling the air flow therethrough.

21. A liquid fuel burner of the class described, comprising a chamber of greater length than breadth having an outlet for combustion products at one end and means for admitting mixed liquid fuel and air at the other end and containing an igniter, said fuel admitting means being disposed to di-

rect its mixture transversely to the axis of 25 said space.

22. The combination with an engine intake having a carburetor, said carburetor comprising a liquid jet and air entrance arranged for making a spray mixture containing fuel in liquid state, a throttle for said carburetor, and a choker device functioning independently of the position of the throttle for restricting the air entrance so as to increase the suction effect acting on said liquid jet and thereby enrichen said spray mixture, a suction-operated burner connected to the suction intake, said burner comprising means operated by suction to produce a mixture of fuel and air and an electric igniter for said mixture, and means for automatically venting air into said intake when the operation of said choker device increases the suction therein above the predetermined limit.

In testimony whereof, I have signed this specification.

JOHN GOOD.
